In the upper part of the top portion are holes or perforations, and below the encircling bead of the rounded top portion are also holes or perforations.

15 In the accompanying drawings Figure 1 is a side view of a cane or umbrella head embodying my design, and Fig. 2 is a top view of the same.

A denotes the rounded top portion of the handle or head, and B the slightly tapering or cylindrical lower portion of the same. En- 25 circling the top portion A, and about midway thereof, is a bead *a*; and at the bottom of the lower portion B is also an encircling bead *b*. Formed in the top of the upper portion A are holes or perforations *c*, and in the lower portion of said top part A, below the bead *a*, are also holes or perforations *d*.
